(74) Attorney, Agent, or Firm — FisherBroyles, LLP;
Jason M. Pass(57) CLAIM

The ornamental design for a mounting hook, as shown and described.

DESCRIPTION

FIG. 1 is a front left perspective view of a mounting hook, according to my design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings illustrate portions of the mounting hook that form no part of the claimed design.
